US0D1014405S

(12) United States Design Patent (10) Patent No.: US D1,014,405 S
(45) Date of Patent: * Feb. 13, 2024

(54) CAR POCKET

(71) Applicant: Terrell Cannon, Moreno Valley, CA (US)

(72) Inventor: Terrell Cannon, Moreno Valley, CA (US)

() Term: 15 Years

(21) Appl. No.: 29/760,954

(22) Filed: Dec. 4, 2020

(51) LOC (14) Cl. 12-16

(52) U.S. Cl.

USPC D12/415; D3/303

(57)

The ornamental design for a car pocket, as shown and described.

DESCRIPTION

FIG. 1 is a front perspective view of my new design;

FIG. 2 is a front perspective view thereof, shown in an alternate configuration.

FIG. 3 is a rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The broken lines depict portions of the car pocket that form no part of the claimed design.

1 Claim, 5 Drawing Sheets
